T. S. KIZER.
SOCKET WRENCH.
APPLICATION FILED SEPT. 3, 1920.

1,395,585.

Patented Nov. 1, 1921.

UNITED STATES PATENT OFFICE.

THOMAS S. KIZER, OF CHATTANOOGA, OKLAHOMA.

SOCKET-WRENCH.

1,395,585.

Specification of Letters Patent.

Patented Nov. 1, 1921.

Application filed September 3, 1920. Serial No. 407,840.

To all whom it may concern:

Be it known that I, THOMAS S. KIZER, citizen of the United States, residing at Chattanooga, in the county of Comanche and State of Oklahoma, have invented certain new and useful Improvements in Socket-Wrenches, of which the following is a specification.

This invention relates to an improved 10 socket wrench and has as one of its principal objects to provide a device of this character wherein the wrench jaws may be readily positioned to accommodate different sized nuts.

15 A further object of the invention is to provide a wrench wherein the jaws may be wedged into engagement with a nut and wherein the wedging action tending to draw the jaws together may be increased simply 20 by increasing the forward pressure against the jaws.

25 And the invention has as a still further object to provide a wrench which will be characterized by entire structural simplicity and which will provide a rugged tool.

Other and incidental objects will appear hereinafter.

In the drawings:

Figure 1 is a perspective view of my invention 30 proved wrench showing the jaws thereof projected,

Fig. 2 is a vertical sectional view showing the wrench jaws retracted, this view more clearly bringing out the structural details 35 of the wrench,

Fig. 3 is a transverse section on the line 3-3 of Fig. 2, looking in the direction of the arrows,

Fig. 4 is a perspective view showing one 40 of the wrench jaws in detail, and

Fig. 5 is a sectional view showing a slight modification of the invention.

In carrying the invention into effect, I employ a hollow wrench head 10 enlarged 45 toward its lower end and provided at its upper end with a socket 11 for receiving a stock. Formed in the head to open through the lower end thereof are oppositely disposed internal guide channels 12 each substantially T-shaped in cross section and the bottom walls of which provide upwardly inclined wedging shoulders 13. Slidable upon the wrench head are companion jaws 14. These jaws are preferably provided with an 50 angular serrated jaw faces 15 and rising from the jaws are jaw shanks 16. The shanks 16

are tapered longitudinally and are substantially T-shaped in cross section so as to slidably fit freely in the guide channel 12, the outer sides of said shanks defining upwardly inclined wedging faces 17 coacting with the shoulders 13 of the channels. Formed in the outer sides of the shanks are longitudinal grooves 18 and threaded through the wall of the wrench head to 60 freely engage at their inner end portions in said grooves are locking pins 19 slidably connecting the jaws with the wrench head. The jaws may, of course, be shaped to fit a square nut as shown in the drawing or may 65 be shaped to fit a hexagonal nut, and formed in the jaw shanks at their inner ends are mating recesses 20 adapted, when the jaws are fitted over a bolt to engage a nut thereon, to receive the projecting end of the bolt. 70

As will now be readily understood in view of the preceding description, by simply holding the wrench head with its lower end presented downwardly, the jaws 14 will gravitate to projected position, the jaws being progressively spread in their downward movement. Consequently the jaws may then, as suggested in Fig. 1, be readily engaged over a nut, when by pressing downward upon the wrench head, the shoulders 13 of the head 85 will act against the faces 17 of the jaw shanks for forcing the jaws toward each other with a wedging action and binding the jaws in engagement with the nut, the effect being to retract the jaws upon the head. 90 Thus, the jaws may be caused to tightly grip the nut and, as will be seen, the gripping action of the jaws may be increased by simply increasing the forward thrust against the wrench head. As will be noted, the 95 wrench head is formed with a flat forward end edge while the jaws, at the base of each of the jaw shanks, are respectively provided with a flat face. Consequently, when the jaws are completely retracted, the forward edge of the head will abut the flat faces of the jaws for sustaining forward thrust against the head and relieving the jaws of any inward pressure toward each other. As will be appreciated, this feature will be 100 found of advantage when it is desired to simply engage the jaws about a nut without gripping the nut, mutilation being thereby avoided.

I accordingly provide a highly effective wrench structure and a socket wrench which is adapted for a wide range of use. 105 110

In Fig. 5 of the drawings, I have shown a slight modification of the invention. In this modification, a conical wrench head 21 is employed. At its upper end this head 5 is provided with a socket 22 as in the preferred construction, and formed in the head are inwardly converging channels corresponding to the channels 12. In these channels are mounted coacting jaws 23 slidably 10 connected with the head by locking pins 24 corresponding to the pins 19 of the preferred construction. The jaws 23 are identical with the jaws 15 as disclosed in the preferred embodiment of the invention 15 with the exception that the jaws 23 are formed with sloping outer faces conforming to and providing a continuation of the sloping outer face of the head 21. Surrounding the head is a vertically slidable locking ring 20 25. This ring may be moved upwardly upon the head so that the jaws may be positioned downwardly to engage a nut, when the ring may then be moved downwardly to surround the jaws, locking the jaws in engagement with the nut. By forcing the ring downwardly over the jaws, the jaw shanks may be relieved of any stress thereon tending to separate the jaws and when the wrench is turned for rotating the nut the 30 ring will, of course, resist movement of the jaws away from each other. Projecting from the upper end portion of the head is a stop pin 26 for limiting the ring against upward displacement.

35 Having thus described the invention, what is claimed as new is:

1. A wrench including a head provided with converging shoulders, and coacting jaws slidably connected with the head and 40 having shanks substantially triangular in

cross section and provided with inclined faces coacting with said shoulders whereby the jaws will be urged toward each other as the head is advanced upon the jaws, corresponding faces of the shanks abutting when the jaws are closed. 45

2. A wrench including a head provided with guide channels substantially T-shaped in cross section, the bottom walls of said channels providing inclined shoulders, and coacting jaws having shanks substantially T-shaped in cross section and slidably fitting in said channels, the shanks having inclined faces coacting with said shoulders whereby the jaws will be urged toward each other as the head is advanced upon the jaws. 50

3. A wrench including a head provided with inclined shoulders, and coacting jaws slidably connected with the head and having jaw shanks rising therefrom and provided with inclined faces to coact with said shoulders whereby the jaws will be urged toward each other as the head is advanced upon the jaws, the jaw shanks having confronting faces disposed to abut when the jaws are 60 closed and the jaws being formed with flat faces at the junctions of the shanks therewith for engagement with the forward end 65 of the head to sustain forward thrust of the head in the closed position of the jaws. 70

4. A wrench including a head having a sloping exterior wall, coacting jaws slidably mounted upon the head and having sloping exterior walls conforming to the inclination of the wall of the head, and a locking ring 75 slidable upon said wall of the head and movable to surround the jaws coacting with the sloping walls thereof.

In testimony whereof I affix my signature.
THOMAS S. KIZER. [L. S.]
